UNITED STATES PATENT OFFICE.

LONZO B. BETHARDS, OF CHICAGO, ILLINOIS.

STORE-SERVICE APPARATUS.

972,432.

Specification of Letters Patent. Patented Oct. 11, 1910.

Application filed September 20, 1909. Serial No. 518,651.

To all whom it may concern:

Be it known that I, LONZO B. BETHARDS, a citizen of the United States, residing at Chicago, in the county of Cook and State 5 of Illinois, have invented certain new and useful Improvements in Store-Service Apparatus, of which the following is a description, reference being had to the accompanying drawings, forming a part of this specification, in which corresponding letters of reference in the different figures indicate like parts.

The object of my invention is to overcome the common objection heretofore made 15 to that style of store-service apparatus commonly known as the "spread-wire" type, viz.; that the handle of the main propelling lever projects so low when in its abnormal position that it is liable when reversed by 20 the operator at the opposite station in the act of returning the car, to injure one who may be standing near it.

The primary object of my invention is to overcome this difficulty by providing a supplementary handle or hand-controlled lever, which shall be so constructed as to return 25 automatically to an elevated position as soon as the hand of the operator is removed therefrom after forwarding the car.

A further object is to so construct said 30 device that the catch by which the car is held at the sending station may be released thereby before any tension is placed upon the wires to propel the car. Moreover, it 35 is my purpose to provide means in connection with said handle for reversing the pivoted bar to which the wires are attached at the sending station for the purpose of returning the car in an emergency.

I accomplish said objects in the manner 40 hereinafter more particularly described and definitely pointed out in the claims.

In the drawings, Figure 1 is a side elevation 45 of a portion of a store-service apparatus including a car, portions of the wire-way and the propelling mechanism embodying the features of my improvement, the parts being shown in the positions in which they would appear when ready to release and forward 50 the car; Fig. 2 shows the actuating hand-lever, the pivoted wire supporting bar and wires in the respective positions in which they would appear after forwarding the car; Fig. 3 is an enlarged detail view 55 of a portion of the wire supporting bar, and

Figs. 4 and 5 are views of modified constructions which, in addition to the modified features, show the wires reversed as to direction.

Referring to the drawings, 1 represents 60 the usual supporting plate connected in any well-known way to a stationary structure, to which plate is secured a clevis 2, having a bar 3 jointedly connected to its forward end as shown at 4. A link 5 having one 65 end of a wire 6 attached thereto, is jointedly connected at 7 near the upper end of the bar 3, while a similar link 8 has one end connected in like manner at 9 to the lower end of said bar and the other end to a wire 10. 70 The bar 3 is substantially the same as that heretofore in common use except that it is modified in shape to conform to the new conditions and is without a handle at its rear end. A combined spring buffer and catch 75 11 of well-known construction is attached to the forward end of said bar in position to engage a tooth 12 upon a car 13 when the bar is in its normal horizontal position, as shown in Fig. 1.

Pivottally connected to the bar 3 by means of a pin 14 arranged to pass through a slot 15 in said bar, is a bifurcated lever 16, the arms of which, commencing at the rear end of said bar are extended upon opposite 80 sides thereof to a position slightly beyond the forward end, so as to lie normally beneath the catch 11. The lever 16 is provided with a handle 17 at its rear end where the arms of the forked portion are joined. 85 The forward portion of the lever is made somewhat heavier than that of the rear so as to counterbalance the handle. When the car is at the station and the bar 3 is in a horizontal position, as shown in Fig. 1, the 90 rear portion of the lever is brought into contact with any suitable stop above it, such, for example, as the supporting bar or the rear of the clevis 2 and is held in the position indicated in said figure with its 100 forward end immediately beneath and in contact with the catch 11. A notch 18 is formed in the under side of said lever near the handle, which is adapted to engage with the projecting ends of the pivot-pin 9 in 105 the end of the bar 3.

The operation of said device is as follows: When the several parts are in the respective positions shown in Fig. 1, the operator, for the purpose of forwarding the car, grasps 110

the handle 17 and pulls downwardly upon it. The lever 14 being in engagement at its rear end with the pin 9, causes the bar 3 to be moved with it. The first result of 5 this action causes the catch 11 to be lifted out of engagement with the part 12, thereby releasing the car. The continued movement of the handle causes the bar 3 to assume the position shown in Fig. 2, but as 10 soon as the handle is released the forward portion of the lever being heavier, immediately causes the handle to be tilted upwardly out of the way. A pin 19 upon the bar 3 acts as a stop to limit the movement 15 of the lever which is retained in the position shown in Fig. 2 until the bar 3 is reversed by a similar movement at the opposite end of the line for the purpose of returning the car.

20 It sometimes happens that it is desirable for an operator at a given station to return the car thereto without aid from the operator at the opposite end. This may be accomplished by returning the bar 3 to its 25 normal position. In order that the lever 16 may be utilized to make a back pull for this purpose, I provide the slot 15 and the notch 18, which latter extends rearwardly so as to form a finger 20 thereon. The finger 30 is normally out of engagement with the pin 9, but when the operator wishes to return the car, he places the lever against the pin 9, and pushes upwardly thereon until the finger 19 is in engagement with the pin 9, when a back-pull serves to restore the parts to the respective positions shown in 35 Fig. 1.

In Figs. 4 and 5 I have shown a different 40 form of buffer-catch 21 adapted to operate with a tilting, spring-controlled yoke 22, upon the car. The lever 23 is pivoted at 24 upon the same axis as that of the bar 25, to which the wires 6 and 10 are connected, said lever being bent downwardly at its 45 forward end beneath the pin 26 of the yoke for the purpose of releasing the latter. A lug 25^a is formed upon each side of the bar 25 near its forward end, with which the lever 23 engages to actuate the bar 25 as soon as the car is released. A pin 25^b is 50 also formed upon the bar 25 to limit the movement of the lever when the bar is in an abnormal position. Instead of moving the entire lever longitudinally, as above described, when it is necessary to reverse the bar 25, I move the handle only. The handle 55 27 is recessed, as shown, and slidably mounted upon the rear end of the lever 23, being connected therewith by means of a pin 28, Fig. 4, projected through a slot 29 in the lever. A spring 30 in the recess serves to retain the handle in a normal position. A lug 31, having an opening or recess 32 therein is formed upon the handle, said recess being in position, when the handle is

pushed forward, to receive the rear end 33 of the bar 25 and lock the two together. This feature is only intended to be used for the purpose of returning the car in an emergency, as above described.

An important advantage of my improvement is that it enables a much longer handle to be used than is ordinarily employed, thereby making the action easier, while the bar to which the wires are attached may also 70 be made longer. All danger of injury to those standing near when the lever is unexpectedly reversed is avoided, as a result of this construction.

A further advantage is that a positive 80 catch may be insured to hold the car at the station, while the lever enables the same to be positively released by a single act before spreading the wires and that with but a slight effort, whereas heretofore the release 85 has required an excessive exertion on the part of the operator.

Having thus described my invention, I claim:—

1. In a store service apparatus, the combination of a double wire-way, a car mounted thereon, a catch mechanism for normally locking the car at the station, a pivoted wire-spreading bar, an independently pivoted hand lever having its forward end in operative proximity to said catch for releasing the same when moved from a normal position and means for causing an engagement between said hand lever and wire spreading bar after the release of said catch.

2. In a store service apparatus, the combination of a double wire-way, a car mounted thereon, a catch mechanism for normally locking the car at the station, a pivoted wire-spreading bar, an independently pivoted hand-lever, having its forward end in operative proximity to said catch for releasing the same when moved from a normal position, means for causing an engagement between said hand lever and wire spreading bar after the release of said catch, and means for detachably locking said lever and bar together during a backward movement of the two, to return the car by positive action to its normal position.

3. The combination with a double wire-way and car of the class described, of a pivoted wire-spreading bar, an independently pivoted lever for actuating said bar to spread the wires, means for returning said lever to a predetermined position when released from the hand of the operator, and means for abnormally locking said lever and bar together to return the former to its normal position.

4. The combination with a double wire-way and car of the class described, of a pivoted wire-spreading bar, an independently pivoted lever for actuating said bar to spread the wires, means for returning said lever to a predetermined position when released from

the hand of the operator, and a normally disengaged catch mechanism for locking the lever to the bar to enable the latter to be positively reversed for returning the car in 5 an emergency.

In testimony whereof, I have signed this specification in the presence of two subscr-

ing witnesses, this 18th day of September 1909.

LONZO B. BETHARDS.
